UNITED STATES PATENT OFFICE

2,006,747

GASOLINE TANK CLOSURE MEANS

Oliver C. Ritz-Woller, Chicago, Ill.

Application March 10, 1932, Serial No. 597,948

20 Claims. (Cl. 220—24)

My invention relates to closure means for the gasoline tanks of automobiles, and it has for its object the provision of a new and improved form and arrangement of parts by which improved 5 clamping means may be provided capable of being released readily either by a straight pull thereon or by a combination pull and rotary movement, by which such rotary movement of the body of the cap may be effected without a corresponding 10 rotary movement of the clamping members by which the cap is secured in position, by which an improved mounting for the clamping members on the body of the cap is attained so as to strengthen 15 the device and prolong its life, by which the difficulty and labor of assembling the device is cut to a minimum while at the same time the parts are very firmly secured together, by which the device is protected from catching on the spout of the tank during the operation of removing 20 the cap from closing position, by which an improved vent through the cap is provided, by which the spring clamping means are prevented from being bent at the intermediate portions of their bases when the cap is being applied to a tank or being removed therefrom, and by which the device is improved in sundry details as hereinafter set forth.

The preferred means by which I have accomplished my several objects are illustrated in the 30 drawing and are hereinafter specifically described. That which I believe to be new and desire to cover by Letters Patent is set forth in the claims.

In the drawing.—

35 Fig. 1 is a central vertical section through the preferred form of my closure cap means in position upon the usual type of filling spout also shown in section;

Fig. 2 is a side view of one of the spring clamp- 40 ing devices employed in the construction of Fig. 1;

Fig. 3 is a bottom plan view of the plate by which the spring clamping devices are mounted in position, such clamping devices being also shown, partly in section; and

45 Fig. 4 is a top plan view of the filling spout member of a gasoline tank.

Referring now to the several figures of the drawing, in which corresponding parts are indicated by the same reference characters, 10 indicates the gasoline tank of any approved form having a tubular filling spout 11 of the usual style mounted thereon such spout in the construction shown being mounted in position by means of an outwardly extending flange 12. As is best shown 55 in Fig. 1, the upper end of the spout 11 is provided

with an inwardly and downwardly turned flange portion 13 which terminates at a short distance from the upper end of the spout. As is shown in Fig. 4, the flange 13 is notched at opposite sides, as indicated at 14, the flange at one side of each of said notches being of increasing width circumferentially thereof up to a point a short distance from the other notch, at which point a shoulder 15 is provided. This arrangement is provided for the purpose of enabling two lugs inserted through 10 the notches 14 to be turned into position underneath the flange 13 for effecting a bayonet slot connection therewith if desired.

5 My improved closure cap comprises a disc 16 of sheet metal provided with a flaring portion 17 near its outer edge which terminates in a cylindrical flange portion 18. In the construction shown the plate 16 is covered about its edge and across its upper face with a plate 19 of polished aluminum which extends across the outer face 20 of the flange 18 and is spun thereabout as indicated at 20 for holding the parts securely together.

Upon the bottom face of the plate 16, I have mounted two cork gaskets 21 just inside of the flaring portion 17, such gaskets in the construction shown being held in position by means of a plurality of tongues 22 struck up from the plate. These gaskets are designed to correspond in size to that of the upper end portion of the spout 11.

25 At its central point, the plate 16 is provided with an opening, the marginal portion of the metal about the opening being offset with respect to the adjacent portion of the plate so as to provide a shallow circular recess 23 within which I have mounted a metal disc 24. A second metal disc 25 is provided which has its outer edge portion offset slightly with respect to the major portion of the disc so as to have a working fit in the central opening of the plate 16.

30 On the bottom of the disc 25, I have mounted two spring clip members of substantially the form shown in Fig. 2. Each of said clips comprises a base 26 of spring metal having arms 27 at an angle thereto at each end with arms 28 doubled back upon the arms 27, the base 26 and 35 the several arms being all formed integrally with each other, in the construction shown. As is best shown in Fig. 1, where a portion of one of the arms 28 is broken away, each of the arms 28 is 40 in the form of a channel longitudinally of the 45 arm, both of such arms being bowed outwardly at their intermediate portions. As a result of this construction, the arms 28 are adapted to be forced inwardly toward each other by a camming action when the clips are forced into engage- 50 55

ment with a part such as the spout 11. When the arms 28 are forced inwardly toward each other, the distortion of the metal takes place in the arms 27 or in the bases 26 rather than in the arms 28 by reason of the reinforcement of the arms 28 brought about by their channel formation.

In the construction shown, the clips are mounted at right angles to each other across the bottom face of the disc 25, the base 26 of one of said clips being offset slightly as shown in Fig. 1 for causing the bases to have in effect a notched inter-engagement with each other. For holding the clips in position upon the disc 25, I have provided a plate 29 which engages the bottom faces of the base portions 26, such plate 29 being provided with bending tongues 30 at its corners which are adapted to extend through suitable openings in the plates 25 and 24, having their upper ends bent down against the top face of the plate 24, as is clearly shown in Fig. 1. The arrangement is such that the clips and the mounting plates 24, 25 and 29 are easily rotatable with respect to the plate 16. With the tongues 30 bent down for holding the plates 24, 25 and 29 tightly together with the base portions 26 of the clips interposed between the plate 29 and the disc or plate 25, the base portions 26 of the clips are held substantially against bending at their intermediate portions regardless of how much force is applied for forcing the arms 28 toward each other.

As is best shown in Fig. 1, a loop 31 is provided on the bottom face of the plate 29 for attaching a mounting chain or link in position thereon. In the construction shown, the loop 31 is struck up from the metal of the plate 29.

By the use of my construction as above described, my improved cap can be moved into locking engagement with a filling spout such as the spout 11 as shown, with the spring clip in any angular position. In some positions, both of the clips will have operative engagement with the flange 13, but in any position the arms 28 of at least one of the clips will have operative engagement with the flange so as to hold the cap securely in position. By reason of the revolvable mounting of the clips upon the plate 16, when the cap has been pressed to its operative engagement with the filling spout as above described, when an operator applies pressure to the cap for rotating the cap, the clips are permitted to remain in unchanged position with respect to the flange 13 so as to prevent the clips from becoming improperly engaged with the flange portions at the ends of the notches 14.

As is clearly shown in Fig. 1, the flaring portion 17 of the plate 16 is provided at one point with an opening 32 therethrough for permitting the entrance of air between the plates 16 and 19. The air between said plates is free to pass into the tank 18 through the openings in which the tongues 30 are mounted. My cap is thus properly vented in such a manner as to prevent gasoline line from escaping by a splashing action.

While I prefer to employ the form of construction as shown in my drawing and as above described, it is to be understood that my invention is not limited to such form except so far as the claims may be so limited by the prior art.

I claim:—

1. In a closure means for a gasoline tank, the combination of a closure plate adapted to seat on the upper end of the filling spout of a tank, a clip having a base portion extending transversely

across the spout and having outwardly bowed clamping arms extending longitudinally of the spout at opposite sides thereof for camming engagement with the spout, and means rotatably connecting said base portion of the clip with said closure plate affording free and unlimited rotation of the clip with respect to said plate independently of any yielding movement of the clip.

2. In a closure means for a gasoline tank, the combination of a closure plate adapted to seat on the upper end of the filling spout of a tank, a clip having a base portion extending transversely across the spout, having spring arms extending longitudinally of the spout from the ends of the base portion, and having outwardly bowed clamping arms extending longitudinally of the spout from the ends of said spring arms at opposite sides of the spout, and means rotatably connecting said base portion of the clip with said closure plate.

3. In a closure means for a gasoline tank, the combination of a closure plate, and means for securing said closure plate detachably in position on the filling spout of a tank, comprising a spring clip having a base portion in position to extend transversely of the spout, spring arm portions formed with said base portion and extending normally at about right angles with respect to said base portion, and comparatively much stiffer arm portions turned backwardly on said spring arm portions for entering the spout longitudinally thereof and bowed outwardly at their intermediate portions for a camming engagement therewith, said second named arm portions being of a length to extend upwardly beyond the spout for facilitating removal of the device from the spout.

4. In a device of the type described, the combination of a closure plate, a clip comprising a spring base portion extending across the inner face of the plate and spring arm portions formed on opposite ends of said base portion at an angle with respect thereto for securing the plate in operative closure position, and means comprising a pair of clamping plates secured together at opposite faces of said closure plate adapted to hold said base portion in position on said closure plate so as to be revolvable thereon.

5. In a device of the type described, the combination of a closure plate, a clip comprising a spring base portion extending across the inner face of the plate and spring arm portions formed on opposite ends of said base portion at an angle with respect thereto for securing the plate in operative closure position, and means comprising a pair of clamping plates secured together at opposite faces of said closure plate adapted to hold said base portion in position on said closure plate so as to be revolvable thereon and adapted to hold the base portion substantially against bending at an intermediate point when said arms are displaced towards or from each other.

6. In a device of the type described, the combination of a closure plate having an opening therethrough, a clip comprising a base portion extending across said opening on the inner face of the plate and arm portions extending at an angle to said base portion at opposite ends thereof for securing the plate in operative closure position, a pair of clamping plates at opposite faces of said closure plate so as to be revolvable with respect to said opening in said closure plate, and means for securing said clamping plates together and for mounting said clip firmly thereon.

7. In a device of the type described, the com-

5 bination of a closure plate having an opening therethrough, a clip comprising a base portion extending across said opening on the inner face of the plate and arm portions extending at an angle to said base portion at opposite ends thereof for securing the plate in operative closure position, a pair of clamping plates at opposite faces of said closure plate so as to be revoluble with respect to said opening in said closure plate, and
 10 means for securing said clamping plates together and for mounting said clip firmly thereon and serving with the adjacent one of said clamping plates to hold said base member substantially against bending at an intermediate point when
 15 said arms are displaced towards or from each other.

8. In a device of the type described, the combination of a closure plate having an opening therethrough, a clip comprising a base portion extending across said opening on the inner face of the plate and arm portions extending at an angle to said base portion at opposite ends thereof for securing the plate in operative closure position, a pair of clamping plates at opposite faces
 20 of said closure plate with one of said last named plates offset at its middle portion for fitting said opening in the closure plate, and means for securing said clamping plates together and for mounting said clip firmly thereon so as to hold
 25 said clip revolubly in position with respect to said closure plate.

9. In a device of the type described, the combination of a closure plate having an opening therethrough, a clip comprising a base portion extending across said opening on the inner face of the plate and arm portions extending at an angle to said base portion at opposite ends thereof for securing the plate in operative closure position, a pair of clamping plates at opposite faces
 30 of said closure plate with one of said last named plates offset at its middle portion for fitting said opening in the closure plate, and a fourth plate having bending lugs on its edge portions adapted to enter registering openings through said clamping plates for securing said clamping plates in position at opposite faces of said closure plate and for securing said clip firmly in position on said plates with the base portion of the clip interposed between said fourth plate and one of
 35 said clamping plates for securing said clip revolubly on said closure plate.

10. In a device of the type described, the combination of a closure plate, two clips each comprising a spring base portion and a spring arm portion at an angle to said base portion at each end thereof for securing said plate in operative closure position, and means for holding said clips in position with said base portions extending across the inner face of said closure plate in crossed relation to each other and comprising a plate having lugs at its edge portions adapted to be bent into gripping relation to its cooperating parts.

11. In a device of the type described, the combination of a closure plate, two clips each comprising a spring base portion and a spring arm portion at an angle to said base portion at each end thereof for securing said plate in operative closure position, the base portion of one of said
 40 two clips being offset at an intermediate point for effecting notched engagement with the base portion of the other clip at right angles thereto, and means for holding said clips in position with said base portions extending across the inner
 45 face of said closure plate and comprising a plate

having lugs at its edge portions adapted to be bent into gripping relation to its cooperating parts and serving to hold said base portions substantially against bending at intermediate points when said arms are displaced towards or from each other. 5

12. In a device of the type described, the combination of a closure plate, two clips each comprising a spring base portion and a spring arm portion at an angle to said base portion at each end thereof for securing said plate in operative closure position, means for holding said clips in position with said base portions extending across the inner face of said closure plate in crossed relation to each other and comprising a plate 10 having lugs at its edge portions adapted to be bent into gripping relation to its cooperative parts, and a loop struck up from the base of said last named plate for connection of a mounting link thereto. 20

13. In a device of the type described, the combination of a spring base portion, spring arm portions on opposite ends of said base portion at an angle to said base portion, and backwardly extending retainer arm portions formed integrally with said spring arm portions but shaped so as to have a strengthening rib longitudinally thereof so that when said second named arms are pressed towards each other the distortion of the parts is limited substantially to the spring 25 arm portions.

14. In a device of the type described, the combination of a spring base portion, spring arm portions on opposite ends of said base portion at an angle to said base portion, and backwardly 30 extending retainer arm portions formed integrally with said spring arm portions but shaped into substantially channel form longitudinally so that when said second named arms are pressed towards each other the distortion is confined 35 substantially to the spring arm portions.

15. In a device of the type described, the combination of a closure plate, a ring gasket secured on one face of said plate, and clip means in the form of spring mounted retainer arms secured on 40 said plate with free end portions adjacent to the plate opposite the inner edge of the gasket inside of the ring and with intermediate bowed portions normally projecting outwardly opposite the face of the gasket. 45

16. In a device of the type described, the combination of a closure plate, a ring gasket secured on one face of said plate, and clip means comprising a base portion extending across the face of the plate, a spring arm mounted on said base portion and extending away from the plate, and a retainer arm mounted on said spring arm and extending toward the plate, having its free end located opposite the inner edge of the gasket inside of the ring and having an intermediate 50 bowed portion normally projecting outwardly opposite the face of the gasket. 55

17. In a device of the type described, the combination of a closure plate, a ring gasket secured on one face of said plate, spring loops in radial 60 position on said plate each comprising an inwardly disposed arm portion extending away from the face of the plate and an outwardly disposed arm portion turned backwardly upon the inwardly disposed arm portion, and means for 65 securing said inwardly disposed arms in position on said plate, said outwardly disposed arm portions being bowed outwardly at their intermediate portions into position opposite the face of the gasket and having their free ends located oppo- 70

- site the inner edge of the gasket inside of the ring.
18. In a device of the type described, the combination of a closure plate, a ring gasket secured on one face of said plate, retainer means for holding said plate in operative closure position, securing means extending through an opening in said closure plate inside of said ring gasket for mounting said retainer means on said plate so as to rotate thereon, and an imperforate cap secured on the outer face of said closure plate, said closure plate having a vent opening therethrough beyond the outer edge of the gasket through which opening air can enter to the space between the cap and the plate for passage thence through said opening in which said securing means is mounted.
19. A new article of manufacture in the form of a strip of flat spring metal bent at two points in slightly spaced relation to provide two oppositely disposed spring arms, said spring arms being reversely bent to provide backwardly ex-
- tending arms each of which is bowed outwardly at its intermediate portion and is pressed into channel formation longitudinally for making the backwardly extending arms very much stiffer than said spring arms.
20. In a closure means for a gasoline tank, the combination of a closure plate, and two clips on said plate and rotatable freely about an axis at right angles to the plate for securing the plate in operative closure position, said clips being formed from strips of flat spring metal bent at spaced points to provide spring arm portions at opposite ends of intermediate base portions and having the end portions of the strips bent reversely to provide mounting arms which are bowed outwardly at their intermediate portions and are pressed into channel form longitudinally, said base portions of the clips being secured in crossed relationship to each other for positioning said mounting arms in spaced relation.

OLIVER C. RITZ-WOLLER.
